Primary Examiner — Brian N. Vinson(74) *Attorney, Agent, or Firm* — Middleton Reutlinger(57) **CLAIM**

The ornamental design for a security light, as shown and described.

DESCRIPTION

FIG. 1 is a higher perspective view of a first embodiment of a security light showing the new design in a non-deployed configuration;

FIG. 2 is a rear perspective view of the security light design of FIG. 1;

FIG. 3 is a front view of the security light design of FIG. 1; FIG. 4 is a rear view of the security light design of FIG. 1; FIG. 5 is a left side view of the security light design of FIG. 1;

FIG. 6 is a right side view of the security light design of FIG. 1;

FIG. 7 is a top view of the security light design of FIG. 1; FIG. 8 is a bottom view of the security light design of FIG. 1;

FIG. 9 is a higher perspective view of the security light design of FIG. 1 in a deployed configuration; and,

FIG. 10 is a lower perspective view of the security light design of FIG. 9.

The broken lines represent unclaimed portions of the security light.
